UNITED STATES PATENT OFFICE

WILLIAM D. ANTRIM, OF GLOUCESTER, NEW JERSEY, ASSIGNOR TO ROBERTS & MANDER STOVE COMPANY, OF PHILADELPHIA, PENNSYLVANIA, A CORPORATION OF PENNSYLVANIA

GAS BURNER

Application filed June 29, 1931. Serial No. 547,731.

The object of my invention is to improve the construction of burners for gas ranges so that the burner section proper can be applied to a mixing chamber section located below the 5 burner section at different depths.

It will be understood that my improved burner can be applied to gas ranges for stoves using ordinary manufactured gas or special gases known as "casing head" gases. When 10 ordinary manufactured gas is used the burner section can be located comparatively close to the mixing chamber and a certain distance away from the top of the stove, but when casing head gases are used the burner will be 15 located at a greater distance from the mixing chamber section and the burner proper can be located comparatively close to the top of the range.

A further object of the invention is to make 20 a bridge piece at the outlet end of the mixing chamber section, which extends into the passage of the burner section so as to deflect the gases as they pass from the mixing chamber section, preventing the gases escaping directly 25 through the openings above the outlet passage in the mixing chamber section, preventing an excess of gas at this point, as it is desirable that the gas be so distributed that all the jets will be substantially even. By 30 making the burner in two sections the neck of the mixing chamber section and the support for the burner section may be of any length desired. The burner section, after the parts are assembled, can be secured to the 35 mixing chamber section and the support retains the burner section substantially level.

In the accompanying drawing:

Fig. 1 is a side view of my improved burner for gas ranges, the two parts of the burner 40 being broken away to more clearly illustrate the invention;

Fig. 2 is a plan view of the mixing chamber section of the burner;

Fig. 3 is an inverted plan view of the upper 45 or burner section proper;

Fig. 4 is a sectional view on the line 4—4, Fig. 1;

Fig. 5 is a sectional view on the line 5—5, Fig. 1; and

Fig. 6 is a detached perspective view show-

ing the neck portion of the mixing chamber and the bridge piece.

1 is the lower section of the gas burner, in which is a mixing chamber 2, which is enlarged at the inlet end 3 and at this end is the 55 usual adjustable slotted cap 4, which can be turned to regulate the amount of air admitted to the burner. In the center of the cap is an opening 5 for the gas pipe. This cap is secured in place after adjustment by a 60 screw or other device. At each side of the lower section of the burner are brackets 7, which in the present instance are slotted as at 8. These brackets rest on the supporting bar of the range. 9 is the upturned neck of 65 the lower section of the burner having a reduced extension 10. This extension in the present instance is tapered and is ground so as to fit the ground surface of the depending portion 12 of the upper section 11 of the burner, as clearly shown in Figs. 1 and 4. The upper section 11 consists of a hollow hub 14 and a series of hollow radiating arms 15, which are perforated at the top as at 16. The hub has an open center 17, which allows air 75 to pass through the upper section to the upper surface of the burner. This air mixes with the mixture of gas and air passing through the mixing chamber, so as to produce the proper flame required.

It will be noticed that the depending portion 12 of the upper portion is at one side of the opening 17 of the upper burner section 11, and in order to deflect the mixture of air and gas as it enters the burner section, a 80 bridge 18 is formed at the end of the neck 9. This bridge piece extends into one side of the hub 14 and acts to distribute the mixture of gas and air to each side of the upper section of the burner and to prevent the gas passing 85 directly to the openings 16 above the neck 9, so that the amount of gas escaping through the perforations 16 in the several arms of the burner will be substantially the same. In order to insure the proper relation of the 90 bridge 18 to the opening in the upper section of the burner, I provide a depending lug 19 on the upper section 11, which extends into a slot 20 in a post 21, projecting from the lower section 1 of the burner, as illustrated in 100

Figs. 1 and 5. While the lug 19 is shown in the upper section of the burner and adapted to a recess in a post on the lower section, it will be understood that the lug may be on 5 the lower section, which would enter a notch in a depending portion of the upper section, without departing from the essential features of the invention.

By the above construction the neck 9 of the 10 mixing chamber section 1 may be of any length desired and the supporting post 21 may also be of any length, depending upon the character of gas used. In the present instance the depending portion 12 of the upper 15 burner section is secured to the neck 9 by a pin 22, but other means of attachment may be provided. The supporting post 21 not only is for the purpose of holding the burner in a horizontal position but it also acts to prevent 20 the turning of the burner section 11 on the neck and straining the pin.

By this invention the improved burner can be used for any type of gas and is particularly adapted for use of gases from oil cracking, 25 known as "casing head" gases, and which consists for the most part of propane or butane, or mixtures of them and other hydro-carbons, gaseous at room temperature. By adjusting the height of the burner from the mixing 30 chamber so as to bring the burner at a proper level in respect to the top of the range, complete combustion is assured, thus preventing the formation of poisonous carbon monoxide and at the same time furnishing the proper 35 B. t. u. per hour (heat).

While this invention is particularly adapted 40 for a burner for gas ranges, it will be understood that it can be used in connection with ordinary gas plates and gas heaters 45 without departing from the essential features of the invention.

I claim:

The combination in a gas burner, of a lower 45 and an upper section, the lower section forming a mixing chamber and having an upturned neck, the end of the neck being tapered and ground, said neck having a bridge piece located above the tapered portion, the upper section forming the burner proper and having 50 a hollow hub and hollow perforated arms communicating with the hub and also having a depending portion fitting over the ground extension of the neck, the inner surface of the projection being ground to form a gas-tight joint between the two sections; means 55 for securing the depending portion of the upper section to the neck; and means for supporting the upper section some distance from the neck.
